THOMAS M. BEARDON, OF GODLEY, TEXAS, ASSIGNOR OF ONE-HALF TO FRANK GIBBS,
OF GODLEY, TEXAS.

SLIDING-DOOR MECHANISM.

1,192,033.

Specification of Letters Patent. Patented July 25, 1916.

Application filed July 11, 1914. Serial No. 850,334.

To all whom it may concern:

Be it known that I, THOMAS M. BEARDON, a citizen of the United States, residing at Godley, in the county of Johnson and State 5 of Texas, have invented certain new and useful Improvements in Sliding-Door Mechanisms, of which the following is a specification.

My invention relates to a new and useful 10 sliding door mechanism, and its object is to provide a pedally operated mechanism whereby a sliding door may be thrown open and again closed without necessitating the use of one's hand, a single slight movement 15 of the foot serving to actuate both the opening and closing of the door.

A further object is to provide a device 20 of the character described that will be strong, durable, simple and efficient and comparatively easy to construct and also one that will not be likely to get out of working order.

With these and various other objects in 25 view, my invention has relation to certain novel features of the construction and use, an example of which is described in the following specification and is illustrated in the accompanying drawing, wherein:

Figure 1 is a view showing in side elevation a sliding door equipped with my novel 30 actuating mechanism, the door being shown in its closed position. Fig. 2 is a horizontal section taken on *a—a* of Fig. 1. Fig. 3 is a vertical section taken on *b—b* of Fig. 1. Fig. 4 is a detail vertical section taken on 35 *c—c* of Fig. 1 showing how the door at its upper edge is guided by rollers engaging a track. Fig. 5 is a section on *d—d* of Fig. 1 showing the rollers which guide the lower 40 edge of the door along a track. Fig. 6 is a detail sectional fragmentary view of the latch mechanism of my door.

Referring now more particularly to the 45 drawing, wherein like reference characters designate similar parts in all the figures, the numeral 1 denotes a sliding door fitting when in its closed position in a doorway formed by a front jamb 2, a rear jamb 3 and a lintel 4, the jamb 3 being vertically slotted as indicated at 4^a to permit sliding displacement of the door.

In the upper edge of the door a pair of 50 rollers 5 are recessed to engage a track 6, and another pair of rollers 5 are recessed in the lower edge of the door to engage a track

7, the engagement of said rollers with the correlated tracks serving to guide the door in its sliding motion to or from its closed position. The lower track 7 will preferably be extended between two sills 8 in 60 crossing the doorway. (See Fig. 5).

In the front edge of the door there is formed a rectangular recess 9 in which there is mounted a latch 10 of bell-crank shape, the upper end of which latch terminates in 65 a semi-spherical head, while the lower arm is hooked at its extremity to engage a latch bar 11 mounted within a recess 12 in the front jamb 2. Just above the recess 12, the jamb 2 is formed with another recess 70 13, receiving the semi-spherical head 14 of a square bolt 15, projecting horizontally through the jamb into the interior of the correlated wall, and carrying within the wall a coiled spring 16 bearing at one end 75 against the jamb and at the other against the collar 17 fast upon the bolt. The effect of said spring is to normally maintain the bolt in a position in which the head 14 of said bolt is retained within the recess 13 as 80 is shown in Fig. 6. With the collar 17 there is pivotally connected the upper end of a normally vertical arm 18 which projects rigidly from a horizontal rock-shaft 19 passing transversely through the wall just 85 above the floor and formed at each side of the wall with foot pedals 20 projecting slightly toward the doorway. It is preferred to journal the end portions of the rock-shaft 19 in small brackets 22 exteriorly secured to the wall, which will hold 90 the rock-shaft to a constant axis of rotation.

In order that the door after reaching its open position may be automatically returned to its closed position, a J-shaped leaf spring 95 23 is mounted upon a stud 24 to which the rear edge of the door comes adjacent to its open position. The force with which the door is thrown open will be spent in distorting the spring 23 when the door comes into 100 contact with said spring and the consequent reaction of the spring will serve to throw the door back to its closed position. When desired, the door may be maintained open by the use of a common lock 25 which is mounted upon the rear door jamb, the bolt of said lock being adapted to engage in an ordinary socket 26 mounted upon the door adjacent to its front edge. Preferably the lock 25 will 105 be of the ordinary key actuated type.

A sliding door equipped with the above described mechanism is superior to the ordinary sliding door since it may be operated with much less effort and will not become soiled through handling. A party wishing to pass through the doorway in either direction will merely exert a slight foot pressure upon the adjacent pedal 20 depressing the same and rocking the shaft 19 so as to displace the upper extremity of the arm 18 toward the doorway putting the spring 16 under compression and bringing the head 14 of the bolt 15 into sudden contact with the upper arm of the bell crank 10. The resulting angular displacement of the bell crank will free its hooked lower arm from the latch bar 11, and the force of impact of the head 14 with the bell crank will throw the door into its open position, in which, as previously specified it will contact with the spring 23.

The invention is presented as including all such modifications and changes as properly come within the scope of the following claim.

What I claim is:

In a device of the character described, the combination with a wall formed with a door-

way, of a sliding door entering the doorway in its closed position, and formed with a recess in its front edge, a bell crank pivoted in said recess having an upper arm formed with a convex head and a hooked lower arm, a latch bar carried by the front door jamb and engaged by the latch member in the closed position of the door, a sliding bolt horizontally mounted in the door jamb perpendicular to the door, its head being opposite to the upper arm of said bell crank, a spring acting upon said bolt maintaining its head spaced from the bell-crank, and a pedally operated mechanism correlated with said bolt to subject the same to a sliding displacement whereby the bell-crank is rocked disengaging it from the latch bar, and the door is thrown open through force of impact of said bolt with the convex head of the latch member.

In testimony whereof I have signed my name to this specification in the presence of two subscribing witnesses.

THOMAS M. BEARDON.
